UNITED STATES PATENT OFFICE.

WILLIAM C. RIEHM, OF KALAMAZOO, MICHIGAN.

SEAT-SPRING.

1,167,597.

Specification of Letters Patent. Patented Jan. 11, 1916.

Application filed February 23, 1915. Serial No. 9,939.

To all whom it may concern:

Be it known that I, WILLIAM C. RIEHM, a citizen of the United States, residing at Kalamazoo, Michigan, have invented certain new and useful Improvements in Seat-Springs, of which the following is a specification.

This invention relates to improvements in seat springs.

10 My improved seat spring is particularly designed by me for use in any relation where similar "seat boxes" are employed.

The main objects of this invention are to provide an improved detachable seat spring 15 for "seat boxes" which may be quickly and easily applied or removed and one which is compact and light in weight so that it may be conveniently carried about and also one which is simple and economical in structure.

20 Further objects, and objects relating to structural details, will definitely appear from the detailed description to follow.

I accomplish the objects of my invention by the devices and means described in the 25 following specification.

The invention is clearly defined and pointed out in the claims.

20 A structure which is a preferred embodiment of my invention is clearly illustrated 30 in the accompanying drawing, forming a part of this specification, in which:

Figure I is a detail vertical section of a structure embodying the features of my invention. Fig. II is a perspective view of the 35 spring supporting bracket with the clamping plate, springs and seat supporting rod removed. Fig. III is a perspective view of the bracket clamping plate.

In the drawing similar reference characters refer to similar parts throughout the 40 several views.

Referring to the drawing, the structure illustrated is an engineer's or locomotive cab seat of the "seat box" type in which a box 1 45 adapted as a tool or storage box is provided with a cover 2 hinged at 3 and adapted as a seat. The cover is provided with upholstery 4. These parts are shown in conventional form.

50 I provide a spring supporting bracket consisting of a vertical arm 5 adapted to be disposed against the inner side of the front wall of the box and an outer horizontal arm 6 resting upon the upper edge of the 55 box and projecting beyond the same. The

inner horizontal arm 7 of the bracket is provided with a vertical depending elongated bearing 8 for the seat supporting bolt or rod 9. The clamping plate 10 is provided with a flange 11 at its upper end adapted to rest on the top of the arm 6, the plate being slotted at 12 to receive the arm. The flange 11 is provided with an outwardly projecting portion 13 having a threaded hole 14 therein for the set screw 15. This set screw is provided with a winged head for convenience in adjusting.

The coiled springs 16 and 17 are arranged one within the other and their upper ends terminate in vertically disposed eyes 19 70 which engage the bolt 20 arranged through the vertical arm 5 of the bracket so that the springs are supported to embrace the bearing 8, the bearing being spaced from the arm 5 to accommodate the bolt 20. 75

The seat supporting rod 9 is arranged through the horizontal eyes 21 at the lower ends of the springs. Nuts 22 are arranged above and below the eyes 21 to secure the rod to the springs so that the rod is yieldingly supported with its upper end above the bracket to support the seat 2, as shown in the drawing.

With the parts thus arranged the spring may be quickly and easily applied to the 85 seat box, the clamp being adjustable so as to accommodate varying thicknesses of wall.

With the parts thus arranged the structure is compact and can be readily carried about in the pocket of the engineer so that 90 he can take the same from one engine to another or remove it when leaving his engine. The structure is economical to produce and at the same time is very effective for the purpose.

Having thus described my invention, what I claim as new and desire to secure by Letters Patent, is:

1. The combination with a box provided with a cover hinged at one side, said cover being adapted as a seat, of a spring supporting bracket having a vertical arm disposed against the inner side of the box and an outer horizontal arm resting upon the upper edge thereof and projecting beyond the same, and an inner horizontal arm provided with a vertical elongated depending bearing spaced from said vertical arm, an adjustable clamping plate having a flange at its upper end projecting at each side 105 110

thereof, the outwardly projecting arm of said flange being adapted to receive a set screw, said plate being slotted below said flange to slidably engage the outer horizontal arm of said bracket, coiled springs arranged one within the other and terminating at their upper ends in vertically disposed eyes and at their lower ends in horizontally disposed central eyes, a spring suspending bolt arranged through said vertical arm and engaging said eyes at the upper ends of said springs whereby the springs are supported to embrace said bearing, a seat supporting bolt arranged in said bearing to project above said bracket and arranged through the eyes at the lower ends of said springs, and nuts on said supporting bolt disposed above and below said horizontal eyes whereby said bolt is yieldingly supported in said bearing.

2. The combination with a box provided with a cover hinged at one side, said cover being adapted as a seat, of a spring supporting bracket having a vertical arm disposed against the inner side of the box and an outer horizontal arm resting upon the upper edge thereof and projecting beyond the same, and an inner horizontal arm provided with a vertical elongated depending bearing spaced from said vertical arm, a clamping plate on said outer horizontal arm, coiled springs arranged one within the other and terminating at their upper ends in vertically disposed eyes and at their lower ends in horizontally disposed central eyes, a spring suspending bolt arranged through said vertical arm and engaging said eyes at the upper ends of said springs whereby the springs are supported to embrace said bearing, a seat supporting bolt arranged in said bearing to project above said bracket and arranged through the eyes at the lower ends of said springs, and nuts on said supporting bolt disposed above and below said horizontal eyes whereby said bolt is yieldingly supported in said bearing.

3. The combination with a box provided with a cover hinged at one side, said cover being adapted as a seat, of a spring supporting bracket having a vertical arm disposed against the inner side of the box and an outer horizontal arm resting upon the upper edge thereof, coiled springs arranged one within the other and terminating at their upper ends in vertically disposed eyes and at their lower ends in horizontally disposed central eyes, a spring suspending bolt arranged through said vertical arm and engaging said eyes at the upper ends of said springs whereby the springs are supported to embrace said bearing, a seat supporting bolt arranged in said bearing to project above said bracket and arranged through the eyes at the lower ends of said springs, and nuts on said supporting bolt disposed

above and below said horizontal eyes whereby said bolt is yieldingly supported in said bearing.

4. The combination with a box provided with a cover hinged at one side, said cover being adapted as a seat, of a spring supporting bracket having a vertical arm disposed against the inner side of the box and an outer horizontal arm resting upon the upper edge thereof and projecting beyond the same, and an inner horizontal arm provided with a vertical bearing, an adjustable clamping plate having a flange at its upper end projecting at each side thereof, the outwardly projecting arm of said flange being adapted to receive a set screw, said plate being slotted below said flange to slidably engage the outer horizontal arm of said bracket, a coiled spring mounted on said bracket to embrace said bearing, and a seat supporting rod supported in said bearing by said spring to project above said bracket.

5. The combination with a box provided with a cover hinged at one side, said cover being adapted as a seat, of a spring supporting bracket having a vertical arm disposed against the inner side of the box and an outer horizontal arm resting upon the upper edge thereof and projecting beyond the same, and an inner horizontal arm provided with a vertical bearing, a clamping plate on said outer arm, a coiled spring mounted on said bracket to embrace said bearing, and a seat supporting rod supported in said bearing by said spring to project above said bracket.

6. The combination with a box provided with a cover hinged at one side, said cover being adapted as a seat, of a spring supporting bracket adapted to rest on the edge of the box and having a vertical arm disposed against the inner side of the box, and a vertical bearing, coiled springs arranged one within the other and terminating at their upper ends in vertically disposed eyes and at their lower ends in horizontally disposed central eyes, a spring suspending bolt arranged through said vertical arm and engaging said eyes at the upper ends of said springs, a seat supporting bolt arranged in said bearing to project above said bracket and arranged through the horizontal eyes at the lower ends of said springs, and nuts on said supporting bolt disposed above and below said horizontal eyes whereby said bolt is yieldingly supported in said bearing.

7. The combination with a box provided with a cover hinged at one side, said cover being adapted as a seat, of a spring supporting bracket adapted to rest on the edge of the box and having a vertical arm disposed against the inner side of the box, and a vertical bearing, a coiled spring terminating at its upper end in a vertically disposed eye and at its lower end in a horizontally disposed

eye, a spring suspending bolt arranged through said vertical arm and engaging said eye at the upper end of said spring, a seat supporting bolt arranged in said bearing to project above said bracket and arranged through the horizontal eye at the lower end of said spring, and a nut on said supporting bolt disposed above and below said horizontal eye whereby said bolt is yieldingly supported in said bearing.

8. The combination with a box provided with a cover hinged at one side, said cover being adapted as a seat, of a spring supporting bracket adapted to rest on the edge of

the box and having a vertical arm disposed 15 against the inner side of the box, and a vertical bearing, coiled springs arranged one within the other mounted on said bracket to embrace said bearing, and a seat supporting rod supported in said bearing by said 20 springs to project above said bracket.

In witness whereof, I have hereunto set my hand and seal in the presence of two witnesses.
